DESIGN FOR A MILK BOTTLE CRATE

John A. Christensen, Arlington, Mass.

Application January 4, 1941, Serial No. 97,811

Term of patent 14 years

To all whom it may concern:

Be it known that I, John A. Christensen, a citizen of the United States, residing at Arlington, in the county of Middlesex, State of Massachusetts, have invented a certain new, original, and ornamental Design for a Milk Bottle Crate, of which the following is a specification, reference being had therein to the accompanying drawing, forming a part thereof.

In the drawings, Fig. 1 is a perspective view, Fig. 2 is a plan view, and Fig. 3 is an end elevational view illustrating a milk bottle crate showing my new design.

I claim:

The ornamental design for a milk bottle crate, substantially as shown.

JOHN A. CHRISTENSEN.
